UNITED STATES PATENT OFFICE.

LEWIS E. GRUBBS, OF LOGANSPORT, INDIANA.

ELECTRIC SAD-IRON.

1,039,120.

Specification of Letters Patent. Patented Sept. 24, 1912.

Application filed March 30, 1911. Serial No. 617,852.

To all whom it may concern:

Be it known that I, LEWIS E. GRUBBS, a citizen of the United States of America, and resident of Logansport, county of Cass, State of Indiana, have invented certain new and useful Improvements in Electric Sad-Irons, of which the following is a specification.

This invention relates to certain new and useful improvements in electric sad irons of that class in which coils are employed, and it has for its objects among others to provide a simplified and improved form of iron of this character having provision for obviating the destructive feature of coils such as heretofore employed in connection with a core of some sort made of brass, iron, mica or the like. By employing a coil without a core I obviate the destructive features of other coils caused by contraction and expansion. By placing the coil in the iron without a core, it is left with plenty of room for contraction and expansion without injuring the coil. By my particular disposition of the coil in the iron body, I obtain a more even distribution of the heat. The coil is so disposed that the iron derives the heat from the bottom and two sides of the coil, covering an area of at least three-fourths of the same, thereby adding to the efficiency of the iron.

I employ a heating element composed of a coil of resistance wire installed in a plurality of separate grooves in the body of the iron located in such positions as to distribute an equal amount of heat to all parts of the surface of the iron. This resistance coil is so constructed as to require no insulation of any kind between the individual branches thereof. The coil is fastened to the rear part of the body of the iron in such a manner that the top or cover can be readily removed when desired without interference in any way with the working parts of the heating element. In connection with an iron of this construction, I employ a plug having tapering sockets for co-operation with tapering terminals on the body of the iron whereby I obtain permanent and firm contact at all times. As the connections become worn, the

tapering effect in the plug adjusts itself automatically to a like tapering effect on the terminals so as to keep a tight connection. I sometimes provide the body of the iron with a guard for the terminals. 55

I aim further at other improvements in the details of construction whereby the manufacture of the device is cheapened and facilitated and better results obtained with less liability of injury or derangement of any of the parts. 60

Other objects and advantages of the invention will hereinafter appear and the novel features thereof will be particularly pointed out in the appended claims. 65

The invention is clearly illustrated in the accompanying drawings, which, with the numerals of reference marked thereon, form a part of this specification, and in which—

Figure 1 is a perspective view of my improved iron. Fig. 2 is a top plan with the cover and the intermediate insulation removed, the securing means or screws being shown in section. Fig. 3 is a vertical section through the entire iron with the plug attached, the section being taken as on the line 3—3 of Fig. 2. Fig. 4 is a vertical cross section as on the line 4—4 of Fig. 2. Fig. 5 is an elevation of the plug. Fig. 6 is a detail on a smaller scale, showing the iron as provided with a guard for the terminals on the body thereof. 70

Like numerals of reference indicate like parts throughout the different views.

Referring to the drawings, 1 is the body of the iron and 2 the cover or top portion thereof. The body is formed with chambers or channels 3, 4, 5, 6 and 7. The channels 3, 4, 5 and 6 extend substantially lengthwise of the body of the iron, the outside chambers 3 and 5 being inclined from the heel toward the toe of the iron, while the chamber 7 connects the rear ends of the said chambers 3 and 6, all as seen best in Fig. 2. Within these chambers or channels is disposed a heating element consisting preferably of a coil 8 of resistance wire, preferably in one continuous element or coil, the terminals of which are disposed in the rear ends of the chambers or channels 4 and 5, as 85 90 95 100

seen best in Fig. 2. These terminals, of which one is designated by the reference numeral 9 in Fig. 3, extend upward into a chamber or cavity 10 in the top 2 of the iron, as seen. 5 These terminals are connected by suitable means, as screws 11 with the plug terminals 12 which extend through the top 2 of the iron and which are made tapering, as seen clearly in Figs. 1 and 3. Suitable nuts 13 10 are employed for holding the same firmly in position, a plate 14 extending across from the two terminals and receiving the nuts, as seen clearly in Fig. 1. Suitable insulation, as mica 15, is employed within this chamber or socket 10 in the top 2 of the iron, as seen in Fig. 3, for an obvious purpose. 15

16 designates a sheet of insulating material, as asbestos, interposed between the top of the body 1 and the adjacent face of the top 2, being preferably seated in a recess 17 in the under face of said top 2, as seen clearly in Fig. 4.

18 is mica or analogous material lining the chambers 3, 4, 5, 6 and 7, as seen in Figs. 20 and 4, for an obvious purpose.

19 is a handle of any suitable construction mounted in the holder 20 secured to the top 2 of the iron in any suitable way, as by the screws 21, see Figs. 1 and 4.

30 The top 2 of the iron is removably secured to the body in any suitable manner, as, for instance, by screws 22. It will be noted that by the construction shown, the top may be readily removed at any time by removing the screws and turning the top to one side without in any wise interfering with the heating element or coil.

23 is the plug. It is composed, preferably of a single piece of fiber having a stud 24, 40 through which pass the wires 25 and 26 from a suitable source of supply of electric current, these wires extending through the stud and out through openings 27 therein, as seen best in Fig. 3, and within openings 45 28 in the plug and into the tapered metallic sockets 29 within openings in the opposite face of the plug, as seen in Figs. 3 and 5, where the ends of said wires are fastened in some suitable manner, as, for instance, 50 by the screws 30, see Figs. 3 and 5, the heads of the said screws being seated in openings 31 in the side of the plug where they are out of the way, yet readily accessible when it is desired to disconnect the 55 wires.

32 is a wire coil around the portion of the wires 25 and 26 adjacent the stud 24, the one end of the coil being connected with the stud and the other carried by the collar 60 33 in any well known way.

In use, the tapered sockets of the plug are engaged with the tapered terminals 12, as clearly shown in Fig. 3, and by this means there will always be a tight connection, and 65 provision is made for wear.

In some instances I may employ a guard 34 secured to the handle support 20 in any suitable way, as by a screw or the like 35, as seen in Fig. 6. This guard extends over the ends of the terminals 12 and protect the 70 same against breakage or injury and into this guard the plug is placed when it is desired to make connection and adapt the iron for use.

Upon reference to Fig. 2, it will be noted that the channels, 3, 4, 5, and 6 are so disposed as to leave wedge-shaped portions 36 75 37 and 38 between the said grooves extending lengthwise of the body. These separate wedge-shaped portions retain the heat and distribute it to all surfaces of the iron 80 85 equally.

By reason of the particular construction of the plug and the attachment of the wires 25 and 26 thereto, all of the strain is taken 85 off of the terminals of the iron and placed upon the plug itself.

Modifications in detail may be resorted to without departing from the spirit of the invention or sacrificing any of its advantages. 90

What is claimed as new is:

1. An electric iron comprising a body having separate grooves forming separate wedge-shaped portions between said grooves 95 and a groove extending across the heel of the iron and connecting the outside grooves, and a coreless heating element composed of one continuous coil of resistance wire disposed within the longitudinal and transverse grooves. 100

2. An electric iron having a body formed with longitudinally extending grooves and a transverse groove at the heel connecting the outermost of said longitudinal grooves, 105 a coreless heating element composed of a continuous coil of resistance wire disposed within said grooves, a top to the iron having a cavity into which the ends of said coil extend for connection with terminals, and terminals on said top with which said ends are connected. 110

3. An electric iron comprising a body having outer and intermediate channels extending lengthwise of said body, the outer 115 channels being inclined from the heel toward the toe, and the intermediate channel connecting the rear ends of said outer channels and a coreless heating element in one continuous unit disposed within said channels with the terminals thereof disposed in the rear ends of two of the longitudinally disposed channels. 120

4. An electric sad iron comprising a body having inclined side channels, a connecting 125 cross channel, and intermediate substantially parallel channels communicating with said side channels, a coil resistance wire forming a coreless heating element disposed in said side, cross and intermediate channels, the 130

terminals of said wire being extended through the body, said body having a chamber to receive the securing means of said terminals, a removable cover, and a non-
5 heat conducting material interposed between said cover and the upper wall of said body and overlying said heating element.

Signed by me at Logansport, Ind., this
27th day of March, 1911.

LEWIS E. GRUBBS.
